UNITED STATES PATENT OFFICE.

HENRY HARLEY PITT, OF LESBURY, ENGLAND.

MACHINE FOR FIRE-FINISHING TUMBLERS AND OTHER GLASS ARTICLES.

1,307,453.

Specification of Letters Patent. Patented June 24, 1919.

Application filed August 7, 1917. Serial No. 184,954.

To all whom it may concern:

Be it known that I, HENRY HARLEY PITT, of The Farm, Christon Bank, Lesbury, in the county of Northumberland, England, 5 glasswork expert, a subject of the King of Great Britain and Ireland, have invented certain new and useful Improvements Relating to Machines for Fire-Finishing Tumblers and other Glass Articles, of which the 10 following is a specification.

This invention relates to machines for fire-finishing tumblers and other hollow glass articles, and has for its object to provide an improved machine for this purpose.

15 A machine for fire-finishing tumblers and other hollow glass articles in accordance with this invention is characterized in that means are provided for passing water, steam, air or other cooling medium through 20 the plugs or stands which receive or support the tumblers or other hollow glass articles during the fire-finishing process, for the purpose of cooling said plugs or stands.

25 The preferred form of machine for fire-finishing tumblers and similar glass articles which fit onto plugs or stands comprises a table or the like carrying a number of rotary plugs or stands adapted to receive the tumblers or the like to be fire-finished, means 30 for rotating or moving said table or the like so as to pass the plugs or stands through a furnace or "glory-hole", and means for admitting and discharging water, steam, air or other cooling medium to and from the interior of each plug or stand to cool same.

35 Means are also provided for alternately raising and lowering the tumblers or the like on the plugs or stands. I may also combine with my improved machine one or more 40 nozzles arranged so as to direct a jet or jets of air on such portions of the exterior of the tumbler or the like as may be required to be protected from excessive heat, as has been done in other machines for fire-finishing 45 pressed glass articles.

I will fully describe my invention with reference to the accompanying drawings wherein,—

50 Figure 1 is a plan of one construction of machine for fire-finishing glass tumblers and embodying my invention;

Fig. 2 is a half sectional elevation to a larger scale of the machine of Fig. 1; and

Fig. 3 is an elevation of a detail.

55 Referring to Figs. 1, 2 and 3 of the drawings, in the embodiment of my invention

therein illustrated, I arrange around the periphery of a horizontal circular table *a* a number of plugs or stands *b* each adapted to receive a tumbler *c* (as shown in Fig. 2) 60 to be fire-finished. The circular table *a* is carried by radial arms *d* from a hub or sleeve *e* free to rotate about a fixed central pivot *f*. The sleeve is rotated in any convenient manner. At one side, the table *a* extends beneath a furnace or "glory-hole" *g* so that, as the table rotates, the plugs *b* carried thereby pass through said furnace. The furnace is constructed of suitably-shaped fire-clay blocks as usual, and may be 65 suspended from an overhead beam or supported from the floor in any suitable fashion. The table *a* runs on balls *h* arranged in a ball-race around the top of a circular fixed frame *j* which is carried by a suitable 70 bed-plate (not shown) which also carries the pivot *f*.

75 Each plug *b* is mounted on a flanged shaft *k* which passes through a hole in the table *a* and is free to rotate therein on balls *m*, 80 and a chain wheel *n* is fitted on the shaft *k* beneath the table, said chain wheel being rotated by a chain *n'* (Fig. 1) which passes around the outer side of the chain wheels of all the plugs and also around a chain wheel 85 *o* loosely mounted on the central sleeve *e* but attached to a toothed wheel *p* driven by a pinion *q* on a vertical shaft *r* which is rotated in any suitable manner. A jockey pulley may be provided for adjusting the 90 chain.

95 Each plug *b* is hollow having an internal chamber *s* through which passes a tube *t* surrounding a central rod or spindle *u*. Water, steam or air is drawn or forced 100 through the chambers *s* of the plugs *b* to cool same and keep them at an even temperature, and the cooling medium may be continuously passed through the plugs in a steady stream or may be alternately admitted to 105 and discharged therefrom, or may be admitted to the plugs only at such times as may be necessary to keep them at the desired temperature. The cooling medium, which may conveniently be water, is supplied under pressure to a central chamber *v* in the hub *e* through a supply pipe *w* and is led from said central chamber through a radial pipe *x*. A port *z* in the shaft *k* of the plug *b* is adapted to register with the outer end 110 of the pipe *x* once during each revolution of said shaft. If desired, more than one

port z may be provided. The port z communicates with an internal passage 2 in the shaft leading to a pipe 3 and a perforated ring 4 within the chamber s from which the 5 water issues. The water is led away from the chamber s through a hole 5 in the shaft from which it drips into a circular drip tray 6 provided around the inside of the frame j . In order that water shall only be supplied 10 to the chamber s when the plug is passing through the furnace g , or for such portion of the travel of each plug as may be desirable, I provide in the pipe x a cock controlled by a lever 7 operated by a rod 8 provided with a roller 9 running on a circular track 10. The track 10 is provided with a raised portion or cam 11 opposite to the furnace g or in such position as may be required so that, when the roller 9 rides over 15 said raised portion, the rod 8 is lifted to raise the lever 7 and open the cock in the pipe x , as shown in Fig. 2, and water or other cooling medium flows to the chamber s . When the roller 9 returns to normal level, 20 the lever 7 is lowered and the cock closed. In this way the water or other cooling medium is only supplied to the chamber s while the plug is passing through the furnace or during such portion of the travel 25 of each plug as may be arranged. It will be understood that a separate pipe x and cock-operating mechanism 7, 8, 9 are provided for each plug b . As the port (or ports) z only communicate with the pipe x 30 once during each revolution of the plug b , the water will issue from the perforated ring 4 in intermittent jets during the passage of the plug through the furnace. By thus cooling the plugs I am enabled to keep 35 the temperature thereof sufficiently low to prevent the tumbler or the like sticking to the plug during the finishing process.

The central rod or spindle u of each plug b is adapted to be alternately raised and 40 lowered or allowed to fall, and in the raised position a head 12 on the rod u projects beyond the top of the plug. The rod u is raised and lowered by a circular switch-back track 13 which is engaged by the lower end 45 of the rod and passes around the inside of the frame j being supported therefrom by brackets 14. The profile of the track is shown in Fig. 3. The tumbler c on the plug b is thus alternately raised by the head 12 of 50 the rod u as indicated in dot-and-dash lines in Fig. 2, and lowered again, which movement, when the plug is passing through the furnace, allows the flame of the furnace to pass to some extent into the interior of the 55 tumbler to smooth and polish the mouth or edge 15 thereof. The reciprocation of the tumbler on the plug also prevents the tumbler contracting onto the plug during 60 cooling.

If desired a groove or recess or a series 65

of concavities may be formed around the plugs as indicated in dot-and-dash lines at 16 in Fig. 2 in such a position that said groove or the like is partially uncovered by the tumbler in its raised position. The 70 groove or the like 16 will permit the flame of the furnace to enter the mouth of the tumbler and insure that the edge 15 thereof is thoroughly smoothed and polished by the 75 flame.

In order to protect the base 17 of the tumbler from excessive heat which would soften and distort same, I provide a series of nozzles 18, 19 suitably fed with compressed air adapted to direct jets of air upon the outside 80 of the tumbler near the base and across the base to prevent the temperature of said portions rising too high. The nozzles may be arranged in any convenient manner and may be supported by or from the walls of the 85 furnace or otherwise conveniently, and a valve or valves will be provided to control said jets of air as required. If necessary additional nozzles may be provided to direct air upon other portions of the article on the 90 plug.

What I claim and desire to secure by Letters Patent is:—

1. A fire-finishing machine for hollow glass articles comprising a movable carrier, 95 a series of hollow article-carrying plugs mounted thereon, said plugs being of a shape corresponding to the interior of the article to be carried thereby, means for advancing the carrier to successively pass each 100 plug and the article mounted thereon through the furnace, and means for supplying jets of cooling medium against the interior of each plug during the movement of the carrier, whereby the interior of the 105 glass article is cooled and thereby prevented from sticking to the plug and from losing its shape.

2. A fire-finishing machine for hollow glass articles comprising a movable carrier, 110 a series of hollow article-carrying plugs mounted thereon, said plugs being of a shape corresponding to the interior of the article to be carried thereby, means for advancing the carrier to successively pass each plug 115 and the article mounted thereon through the furnace, means for lifting the articles slightly off of the carrying plugs, whereby the flames may lick under the edges of the 120 slightly lifted article and between the article and its carrying plug, and means for supplying jets of cooling medium against the interior of each plug during the movement of the carrier, whereby the interior of the glass article is cooled and thereby 125 prevented from sticking to the plug and from losing its shape.

3. In a fire-finishing machine for hollow glass articles, a movable carrier, a series of 130 hollow article-carrying plugs thereon closely

- fitting the glass articles to be treated, means for advancing the carrier to successively pass each plug and the article mounted thereon through the furnace, means for sup-
- 5 plying a cooling medium to the interior of each plug during the movement of the carrier, means normally cutting off the admission of said cooling medium, and for automatically admitting the cooling medium
- 10 successively to each plug while entering and passing through the furnace and for again cutting off the said medium as the plug issues from the furnace.
4. In a fire finishing machine for hol-
- 15 low glass articles a rotary table, a series of hollow article-carrying plugs thereon closely fitting the glass article to be treated, means for rotating the table to successively pass each plug and the article mounted thereon
- 20 through the furnace, means for supplying a cooling medium to the interior of each plug during the rotation of the table, means for automatically and alternately raising and lowering each article from and on to its
- 25 carrier plug, means normally cutting off the cooling medium and for automatically admitting the said medium successively to each plug while this is passing through the furnace and for again cutting off the said medium from the plug as the latter issues from the furnace.
- 30
5. In a fire-finishing machine for hollow glass articles a rotary table, a series of hollow article-carrying plugs thereon closely fitting the glass articles to be treated, means for rotating the table to successively pass each plug and the article mounted thereon through the furnace, means for supplying a cooling medium to the interior of each plug during the rotation of the table, means for automatically and alternately raising and lowering each article from and on to its carrier plug, means for rotating each plug upon its axis during the rotation of the table, means for intermittently admitting the cool- 40
- ing medium to each plug in succession at one or more points in each revolution of the plug upon its axis, means normally cutting off the cooling medium, and for automatically admitting the said medium succes- 45
- sively to each plug while this is passing through the furnace and for again cutting off the said medium from the plug as the latter issues from the furnace.
- In witness whereof, I have hereunto 50 signed my name in the presence of two sub-scribing witnesses.
- HENRY HARLEY PITT.
